Primary Examiner—Cathy Anne MacCormac
Attorney, Agent, or Firm—Larson & Larson, P.A.; James E. Larson[57] **CLAIM**

The ornamental design for a cat hammock, as shown and described.

DESCRIPTION

FIG. 1 is a front view of a cat hammock, showing my new design, the rear view being identical; FIG. 2 is a side elevational view thereof, both sides being identical;

FIG. 3 is a top plan view thereof; and FIG. 4 is a bottom plan view thereof;

FIG. 5 is a front view of an alternate embodiment of a cat hammock, showing my new design, the rear view being identical;

FIG. 6 is a side elevational view of the alternate embodiment, both sides being identical;

FIG. 7 is a top plan view of the alternate embodiment; and, FIG. 8 is a bottom plan view of the alternate embodiment. The broken line illustration of a cat of FIG. 1 forms no part of the claimed design.
